UNITED STATES PATENT OFFICE.

HARRY CHRISTENSEN, OF CHICAGO, ILLINOIS, ASSIGNOR TO ELITE LAMP CO., OF CHICAGO, ILLINOIS.

DESIGN FOR A LAMP.

Application filed February 1, 1926. Serial No. 16,353. Term of patent 3½ years.

To all whom it may concern:

Be it known that I, HARRY CHRISTENSEN, a citizen of the United States, and a resident of the city of Chicago, county of Cook, and State of Illinois, have invented a new, original, and ornamental Design for Lamps, of which the following is a specification, reference being had to the accompanying drawing, forming a part thereof.

The figure is a perspective view of the lamp showing my new design.

I claim:

The ornamental design for a lamp, as shown.

HARRY CHRISTENSEN.
